STOCK REGULATOR

William P. Feeney, Appleton, Wis.

Application October 10, 1935, Serial No. 44,365

8 Claims. (Cl. 92—46)

This invention relates to stock regulators for paper manufacturing machines.

The various known devices for regulating the consistency and flow of stock are all based upon the sound principle that no more solids will pass through an opening of a given size if the stock is thick than will pass through the same size opening if the stock is of relatively lesser consistency. If the pressure of the flowing stock is maintained constant, the difficulty that arises is that when the stock becomes thick and less of it tends to pass through the opening, the stock supply being constant, the stock tends to build up and increase the pressure. This resulting increase of pressure causes more of the thick stock to pass through the opening to the paper machine and hence the regulator ceases to function as one and the desired consistency of stock is not obtained. There have been two schools of thought in connection with the maintenance of a stock of predetermined consistency as it is furnished to the paper machine. One has been the use of this pressure to operate a water valve to control the consistency of the stock by adding water to it. The other has been the use of this pressure to operate a gate to relieve the pressure. In either event this general type of stock regulator makes for control elements involving pressure responsive movable elements, the accuracy, sensitivity, reliability and durability of which are at best questionable.

It is therefore an object of my invention to provide a stock regulator requiring no moving parts, pressure responsive or otherwise with the exception of a manually operable delivery gate.

To this end it is proposed to so predeterminedly design and construct inlet and overflow compartments and a gate controlled opening to the paper machine that when the stock in the inlet compartment becomes thick and there is a tendency for increased pressure such a tendency is avoided as the stock is free to flow unrestricted to the overflow compartment and back to the source of supply. The mere design, relative size and relationship of the compartments, in combination with the manually adjustable gate for varying the size of the delivery opening to the paper machine, constitutes the means for regulating the flow and the consistency of the stock.

The exact nature of my invention will be apparent upon reference to the following specification and appended claims, certain embodiments of my invention being illustrated in the accompanying drawing, in which:

Figure 1 is a top plan view of one form of my invention;

Figure 2 is a view in section taken along line 2—2 of Figure 1;

Figure 3 is a view in section taken along line 5—3 of Figure 2;

Figure 4 is a view similar to Figure 2 of a modified form of my invention.

Referring more particularly to the form of my invention shown in Figures 1, 2, and 3, the device consists of an outer container 1 and an inner container 2 of lesser depth than the outer container and suitably secured to a partition 3, dividing the regulator into three compartments. These compartments are the inlet, overflow and delivery compartments, 4, 5 and 6 respectively.

The inlet compartment is open at the top and at one side adjacent the partition 3 with an opening 8 through which stock is delivered into the delivery compartment 6. This opening is bounded by the ledge 9 and the lower edge of partition 3. It is further restricted transversely by the tapering trough 10 of which the ledge 9 is the bottom. The opening is valve regulated by means of a gate valve 11 which is manually operated by a hand control 12 and a screw shaft connecting the two. The screw shaft has its bearing in a support 14 fixed to the partition 3. As shown in Figure 3 the valve is slidable in guideways 15 and 16 suitably secured to the adjacent wall 2' of the inlet compartment and to the partition 3. The hand control elements 12 are fixed to a rotatable collar 12' in screw threaded relationship with shaft 13 and is supported on a bracket 16. Within the collar is a tubular calibrated scale 17 provided with a slot 18 through which a pointer 19, attached to the shaft protrudes. The position of the pointer on the scale indicates the position of the gate and consequently the nature of the opening between compartments 4 and 6.

The gate is shown to be wider than the opening but of considerably less dimensions vertically. The stock flows, under pump pressure, upwardly through inlet pipe 7 into the inlet compartment 4. As long as the stock is of the desired consistency, as set by the adjusted position of the gate, all the stock continues to flow into the delivery compartment, as illustrated, and out through the delivery pipe 20 to the paper machine.

When, however, the stock becomes thicker than that desired, the flow being restricted by the tapering trough 10 and the valve controlled opening 8, the tendency of the flow of stock is to take the path of least resistance, which in this case

is over the upper edges of the compartment 4. As far as the two sides and the rear end of this compartment are concerned there is no restriction to an overflow and to aid such overflow the upper edges are bevelled outwardly as shown at 5 21. As explained previously, this outer compartment 5 is considerably larger than the inlet compartment 4. The stock flowing over the edges of compartment 4 into compartment 5 passes out 10 the inlet pipe 22 and back into the source of supply to again be pumped into the inlet compartment.

There is a slight increase in pressure when 15 this overflow into the overflow compartment occurs as the volume of thick stock under such conditions will be deeper than if it were thin. This increase in pressure is negligible and is compensated for by the construction of the gate and the tapering trough. In other words, the resistance to overflow over the edges of the inlet compartment is negligible when compared to that offered by the narrow gate. The tapering trough 20 offers slightly more resistance to flow of thick stock than it does to thin stock.

25 Thus by the above described arrangement the additional pressure caused by the flow of thick stock under pressure is automatically compensated for and hence only the stock of desired consistency passes through the gate and into the 30 paper machine. This compensation of pressure and the regulation of flow of stock through the gate and into the overflow or return is automatically controlled without the necessity of any moving parts. Once the manually operable gate 35 is set, the inherent design of the compartments, under a given pressure supply is automatically controlled. In this connection the scale acts as a means of reference for future adjustment of the gate for conditions corresponding to those under 40 which the device has been successfully operated.

The device as above described has proven eminently satisfactory in actual use. However, in following the basic principle outlined, I am aware 45 that certain deviations from the exact arrangement may be made with satisfactory results. For instance in Figure 4, I may build an outer box 1 and an inner box 23. I may also build a portion 50 3' with an outlet opening 8 into the outlet compartment 6, the opening being controlled by the gate 11 as described. In this case the outer compartment 4' constitutes the inlet compartment and is fed with stock under pump pressure 55 through a pipe 7'. As the stock becomes too thick and due to the relatively restricted size of the opening 8 the pressure tends to increase, this pressure is relieved as the stock overflows over the bevelled edges 21 of the box 23 into the inner or 60 overflow compartment 5'. From here the stock flows out through pipe 22' back into the source of supply from which it is again pumped through inlet pipe 7'.

In either form of my device I prefer to have 65 the upper extremity of the opening or gateway 8 approximately on a level with the overflow from the inner box. In the conventional device the gate and gateway is usually either at or near the bottom of the box. This arrangement permits the use of a small gateway due to the pressure of the column of stock. However, it is due 70 to depth of stock above it that a considerable variation in weight occurs. When this stock above the gate becomes very dense it becomes heavier and consequently the pressure on the gate is increased. As the stock becomes less dense it becomes 75 less heavy and consequently the pres-

sure on the gate is decreased. Inasmuch as the top of my gateway is approximately level with the overflow, this cause of variation in pressure on the gate is eliminated. Furthermore, inasmuch as the changes in the size of the gateway 5 occur at the bottom of the gateway, the top of the gateway does not change its position with respect to the position of the overflow.

I claim:

1. A device for regulating the flow and consistency of stock under initial pressure to a paper making machine, comprising an inner and outer box, the latter being appreciably larger and greater in depth, one of said boxes constituting an inlet compartment for stock under initial pressure, the other constituting an overflow compartment as the stock flows over the upper edges of said inner box, said outer box also being divided into a delivery compartment, a restricted passage leading from said inlet compartment to said delivery compartment said passage being controlled as to its size by an adjustable valve. 10 15 20

2. A device for regulating the flow and consistency of stock under initial pressure to a paper making machine, comprising an inner and outer 25 box, the latter being appreciably larger and greater in depth, one of said boxes constituting an inlet compartment for stock under initial pressure, the other constituting an overflow compartment as the stock flows over the upper edges 30 of said inner box, said outer box also being divided into a delivery compartment, a restricted passage leading from said inlet compartment to said delivery compartment, said passage being controlled as to its size by an adjustable valve, 35 whereby when said stock becomes of a consistency denser than a predetermined degree and pressure tends to increase and deliver more of such thick stock, such pressure is relieved as the stock follows the path of least resistance and flows from 40 said inlet chamber through the relatively unrestricted passage into said overflow chamber, the valve and the relation and dimensions of said chambers and passages constituting the sole means for regulating the flow and consistency 45 of stock, under a given initial pressure, that is delivered to said machine.

3. A device for regulating the flow and consistency of stock under initial pressure to a paper making machine, comprising an inner and outer 50 box, the latter being appreciably larger, and greater in depth, one of said boxes constituting an inlet compartment for stock under initial pressure, the other constituting an overflow compartment as the stock flows over the upper edges 55 of said inner box, said outer box also being divided into a delivery compartment, a restricted passage leading from said inlet compartment to said delivery compartment, said passage being controlled as to its size by an adjustable valve, 60 the upper edges of said inner box being bevelled outwardly with respect to the direction of flow of stock from said inlet compartment to said overflow compartment over said edges of said inner box to aid in such flow and reduce said pressure. 65

4. A device for regulating the flow and consistency of stock under initial pressure to a paper making machine, comprising an inner and outer box, the latter being appreciably larger and greater in depth, one of said boxes constituting an inlet compartment for stock under initial pressure, and the other constituting an overflow compartment as the stock flows over the upper edges 70 of said inner box, said outer box also being divided into a delivery compartment, a restricted 75

passage leading from said inlet compartment to said delivery compartment, said passage being controlled as to its size by an adjustable valve, the upper edges of said inner box being bevelled outwardly with respect to the direction of flow of stock from said inlet compartment to said overflow compartment over said edges of said inner box to aid in such flow and reduce said pressure, whereby when said stock becomes of a consistency denser than a predetermined degree and pressure tends to increase and deliver more of such thick stock, such pressure is relieved as the stock follows the path of least resistance and flows from said inlet chamber through the relatively unrestrictive passage into said overflow chamber, the valve and the relation and dimensions of said chambers and passages constituting the sole means for regulating the flow and consistency of stock, under a given initial pressure, that is delivered to said machine.

5. A device for regulating the flow and consistency of stock under initial pressure to a paper making machine, comprising an inner and outer box, the latter being appreciably larger and greater in depth, one of said boxes constituting an inlet compartment for stock under initial pressure, the other constituting an overflow compartment as the stock flows over the upper edges of said inner box, said outer box also being divided 10 into a delivery compartment, a restricted passage leading from said inlet compartment to said delivery compartment said passage being controlled as to its size by an adjustable valve, said restricted passage being so disposed that its upper extremity is approximately level with the 15 upper edges of said inner box.

6. A device for regulating the flow and consistency of stock under initial pressure to a paper making machine, comprising an inner and outer box, the latter being appreciably larger and greater in depth, one of said boxes constituting an inlet compartment for stock under initial pressure, the other constituting an overflow compartment as the stock flows over the upper edges 20 of said inner box, said outer box also being divided into a delivery compartment, a restricted passage leading from said inlet compartment to said delivery compartment, said passage being controlled as to its size by an adjustable valve, the upper edges of said inner box being bevelled outwardly with respect to the direction of flow of 25 stock from said inlet compartment to said overflow compartment over said edges of said inner box to aid in such flow and reduce said pressure, said restricted passage being so disposed that its upper extremity is approximately level with the 30 upper edges of said inner box, said valve being normally disposed so as to close the bottom portion of said restricted opening but movable upwardly to open said bottom portion.

upper edges of said inner box, said valve being of lesser height than said restricted passage and normally disposed so as to close the bottom portion of said restricted opening but movable upwardly to open said bottom portion.

7. A device for regulating the flow and consistency of stock under initial pressure to a paper making machine, comprising an inner and outer box, the latter being appreciably larger and greater in depth, one of said boxes constituting an inlet compartment for stock under initial pressure, the other constituting an overflow compartment as the stock flows over the upper edges of said inner box, said outer box also being divided 10 into a delivery compartment, a restricted passage leading from said inlet compartment to said delivery compartment, said passage being controlled as to its size by an adjustable valve, the upper edges of said inner box being bevelled outwardly with respect to the direction of flow of 15 stock from said inlet compartment to said overflow compartment over said edges of said inner box to aid in such flow and reduce said pressure, said restricted passage being so disposed that its upper extremity is approximately level with the 20 upper edges of said inner box.

8. A device for regulating the flow and consistency of stock under initial pressure to a paper making machine, comprising an inner and outer box, the latter being appreciably larger and greater in depth, one of said boxes constituting an inlet compartment for stock under initial pressure, the other constituting an overflow compartment as the stock flows over the upper edges 25 of said inner box, said outer box also being divided into a delivery compartment, a restricted passage leading from said inlet compartment to said delivery compartment, said passage being controlled as to its size by an adjustable valve, the upper edges of said inner box being bevelled outwardly with respect to the direction of flow of 30 stock from said inlet compartment to said overflow compartment over said edges of said inner box to aid in such flow and reduce said pressure, said restricted passage being so disposed that its 35 upper extremity is approximately level with the upper edges of said inner box, said valve being normally disposed so as to close the bottom portion of said restricted opening but movable upwardly to open said bottom portion.

WILLIAM P. FEENEY.
